UNITED STATES PATENT OFFICE.

GEORGE W. WHITE, OF NEW YORK, N. Y., ASSIGNOR TO P. & F. CORBIN, OF NEW BRITAIN, CONNECTICUT.

DESIGN FOR PLATES OF DOOR-BOLTS.

Specification forming part of Design No. **6,624**, dated April 29, 1873; application filed April 18, 1873.

To all whom it may concern:

Be it known that I, GEORGE W. WHITE, of the city and State of New York, have invented a Design for the Plates of Door-Bolts, of which the following is a specification:

The nature of the said design is fully represented by the accompanying photographic illustration, to which reference is hereby made.

The surface is countersunk, leaving the ornamental border *a* and the scroll-work and leaflets *b* projecting above such countersunk surface. The general character of such ornamental border *a* is shown in the photograph, and consists of groups of leaflets, three in a group, with an intermediate circular indenta-

tion. The scroll-pattern is also fully shown to consist of a compound reverse curved central stem with scroll-branches and leaflets. The knob *d* of the bolt and knob plate *e* are also ornamented, as shown.

I claim as my invention—

The design of the ornamental surface of the bolt-plate, as described and represented.

Signed by me this 15th day of April, A. D. 1873.

GEO. W. WHITE.
